UNITED STATES PATENT OFFICE.

LLOYD W. GOLDER, OF RIVER FOREST, ILLINOIS, ASSIGNOR TO METAL SPECIALTIES
MANUFACTURING COMPANY, OF CHICAGO, ILLINOIS, A CORPORATION OF ILLINOIS.

DESIGN FOR A SIGNAL-LAMP FACEPLATE.

Application filed December 21, 1921. Serial No. 524,028. Term of patent 7 years.

To all whom it may concern:

Be it known that I, LLOYD W. GOLDER, a citizen of the United States, residing at River Forest, county of Cook, and State of Illinois, have invented a new, original, and ornamental Design for a Signal-Lamp Faceplate, of which the following is a specification, reference being had to the accompanying drawing, forming a part hereof.

The figure shows a front view of a signal lamp face-plate, or lamp lens, embodying my new design.

The rear surface of the disk is provided with prisms which show through those portions of the glass not provided with the opaque coating, thus producing a sort of cross-hatched appearance.

I claim:

The ornamental design for a signal lamp faceplate, as shown, and described.

LLOYD W. GOLDER.
